AUTOMATIC FEED MECHANISM FOR
PUNCH PRESSESDavid Lee Morgan, Dayton, Ohio, assignor to
Lucy B. O'Leary, Montreal, CanadaApplication October 25, 1934, Serial No. 749,951
Renewed January 15, 1936

24 Claims. (Cl. 271—2.5)

My invention relates to improvements in automatic feed mechanisms for punch presses and the like, particularly for feeding flat or rolled strips.

5 One object of the invention is to convert circular motion into rectilinear motion along a line parallel to the axis of its circular motion.

Another object of the invention is to provide 10 an inexpensive, efficient automatic feed mechanism than can be attached to and used on any standard punch press with little expense, and that will automatically feed the material past the dies.

In the drawing which illustrates my invention, 15 Fig. 1 is a front elevation of the mechanism.

Fig. 2 is a detail of the manner in which the attachment is made to the shaft.

Fig. 3 is a detail of the carriage or work holder. 20 Number 1 is a conventional punch press with a bed plate 2 and shaft 3. Attached to shaft 3 is a circular plate 4. Affixed to this plate and revolvable about the centre of the shaft is a second plate 5. Plate 5 is fastened to plate 4 by means of two bolts and washers 6—6. Slots 7—7 25 shaped as segments of a circle in plate 5 allow it to be partially rotated about the centre of the shaft. Slidably mounted on plate 5 is a block 8. This block is held in a rectangular opening in plate 5 by two screws 9 and 10, one of which (9) 30 is threaded through the plate 5 and into the block 8 and held in place by the block nut 11; the other (10) is threaded through the plate and pressed against the block 8. By screwing in or out 9 and 10, the block 8 is therefore adjustable 35 in the slot in 5 and can be held rigidly in place in any position along this slot.

Attached to the block 8 is a stud 13 on which is mounted a collar 14, rotatable about the centre of the stud 13 and provided with two studs 40 15—15 which form, with the forked link 16, a universal joint. The other end of 16, which is also forked, is attached to studs on a sleeve 17 45 slidably mounted on a round bar 18 which in turn is rigidly fastened to the bed plate 2. This forked end of 16 is free to rotate on the studs on sleeve 17. One end of a second arm 19 with forks on either end is mounted by a pivot at the centre of 16, and the other end is mounted on a sleeve 20. This sleeve 20 is free to rotate on the 50 bar 18 but is fixed as regards endwise motion by the supports 21 and 22 fastening the bar to the punch press.

The links are so proportioned in length that when the actuating stud 13 is set in the slot at 55 the dead centre of the stroke of the punch press

the bar 19 forms an angle of 45° with the axis of the shaft of the punch press, and equal angles of 90° with the bar 16. This gives the best results in practice. Considerable variations in these angles accomplish the same results. 5

Fixed to the sleeve 17 is a third stud 23. To this stud is fastened a bar 24, which is attached to the sliding bar 25 by another stud 26. This bar 25 is free to slide longitudinally in a slot 27 in bar 24. A tension spring 28 between studs 23 10 and 26 serves to move the bar 25 back and forth when the press is in operation.

To this reciprocating bar 25, which is attached by suitable supports to the bed press, is attached a carriage for carrying the material to be 15 punched. An arm 29, provided with slots to allow adjustment along the bar 25, is connected to the carriage by a slot in the projection 30. This carriage consists of the parts 31, 32, 33, 34, 35, 36, and 37, held together by the bolts 38 and 39. 20 These bolts slide in the slots 40 and 41 in the guide strip 42. This guide strip is held between the stripper plate 44 and the die 47. The carriage carries two feed pawls 43—43 to carry the material forward. Fastened to the guide strip 25 42 are two spring keeper strips 45—45 to hold the material in place in its forward position. A screw 46, attached to the sliding plate 25 in line with bar 18, limits the forward movement of 19 and consequently the feed of the material. 30

The operation of the device is as follows: As the shaft of the punch press revolves, the upper end of 16 moves around in a circle. The sleeve 17 oscillates about the shaft 18 and also moves back and forth in a straight line, the link 19 producing a pantographic motion.

The length of the feed is determined by adjusting the screws 8 and 9 moving the centre of the stud 13 towards or away from the centre of the crank. This length can be more closely adjusted 40 by the screw 46 which prevents the full forward movement of the carriage. The timing of the motion can be adjusted with reference to the position of the die by adjusting the flange 5 about the centre of the shaft, thus ensuring that this 45 motion is made only after the die is clear of the material.

The effect of this mechanism is that the sleeve 17 moves in a straight line in the same direction as the axis of the shaft of the punch press. The 50 link 19 can be omitted, but a downward thrust on top of the sleeve 17 and the bar 18 will ensue. The use of the link 19 is therefore preferable.

While, in order to comply with the statute, the invention has been described in language more 55

or less specific as to structural features, it is understood that the invention is not limited to the specific features shown, but that the means and construction herein disclosed comprise the 5 preferred form of several modes of putting the invention into effect, and the invention is therefore claimed in any of the forms or modifications within the legitimate and valid scope of the appended claims.

10 Having thus described my invention, I hereby claim:

1. The method of changing circular motion into rectilinear reciprocating motion in a direction at an angle to the plane of the circular motion which consists of a link, one end of which is connected to the source of the circular motion and which is free to oscillate in and at right angles to the plane of such circular motion, the other end being slidably mounted on a guide placed at an angle to the plane of the circular motion and being free to oscillate in and at right angles to the direction of the rectilinear motion.

2. The method of changing circular motion into rectilinear reciprocating motion in a direction at an angle to the plane of the circular motion, which consists of a link, one end of which is connected to the source of the circular motion and which is free to oscillate in and at right angles to the plane of such circular motion, a 20 second link one end of which is pivoted to the first link between the ends thereof, and the other end of which is fixed in the direction of the line of rectilinear motion but free to oscillate about that line.

3. The method of changing circular motion into rectilinear reciprocating motion in a direction at an angle to the plane of reciprocating motion which consists of a link, one end of which is connected to the source of the circular motion 40 and which is free to oscillate in and at right angles to the plane of such circular motion, the other end being slidably mounted on a guide placed at an angle to the plane of circular motion and being free to oscillate in and at right angles 45 to the direction of the rectilinear motion, a second link one end of which is pivoted to the first link between the ends thereof, the other end of which is fixed in the direction of the line of rectilinear motion but free to oscillate about that line.

4. A feed for punch presses and the like, comprising a link one end of which is connected eccentrically to the shaft of the press and free to oscillate about and perpendicular to the axis of 55 that shaft, a guide for the other end of the link, attached to the bed of the punch press in a line parallel to the axis of the shaft, the link being slidably mounted on such guide and being free to oscillate in and at right angles to the axis of 60 the guide, a work carriage and means for attaching the work carriage to the sliding end of the first link.

5. A feed for punch presses and the like, comprising a link, one end of which is connected eccentrically to the shaft of the press and free to oscillate about and perpendicular to the axis of 65 that shaft, and a second link one end of which is pivoted to the first link, the other end being attached to the bed of the press and free to oscillate 70 late about an axis parallel to the axis of the shaft, a carriage for the work, and means to connect the carriage to the free end of the first link.

6. A feed for punch presses and the like, comprising a link, one end of which is connected eccentrically to the shaft of the press, and free to 75

oscillate about and perpendicular to the axis of that shaft, the other end of the link being slidably mounted on a guide causing it to move in a line parallel to the axis of the shaft and being free to oscillate in and at right angles to the axis 5 of that guide, a second link, one end of which is pivoted to the first link between the ends thereof, the other end of which is fixed to the bed and free to oscillate about the axis of the guide, a work carriage and means for attaching the same 10 to the free end of the first link.

7. A feed for punch presses and the like, comprising a link, one end of which is connected eccentrically to the shaft of the press and free to oscillate about and perpendicular to the axis of 15 that shaft, a guide for the other end of the link attached to the bed of the punch press in a line parallel to the axis of the shaft, the link being slidably mounted on such guide and being free to oscillate in and at right angles to the axis of the 20 guide, a work carriage, means of attaching the work carriage to the sliding end of the first link, and means for adjusting the amount of motion of said carriage.

8. A feed for punch presses and the like, comprising a link, one end of which is connected eccentrically to the shaft of the press and free to oscillate about and perpendicular to the axis of 25 that shaft, and a second link one end of which is pivoted to the first link, the other end being attached to the bed of the press and free to oscillate about an axis parallel to the axis of the 30 shaft, a carriage for the work, means to connect the carriage to the free end of the first link, and means for adjusting the amount of motion of 35 said carriage.

9. A feed for punch presses and the like, comprising a link, one end of which is connected eccentrically to the shaft of the press, and free to oscillate about and perpendicular to the axis of 40 that shaft, the other end of the link being slidably mounted on a guide causing it to move in a line parallel to the axis of the shaft, and being free to oscillate in and at right angles to the axis 45 of the guide, a second link, one end of which is pivoted to the first link between the ends thereof, the other end of which is fixed to the bed and free to oscillate about the axis of the 50 guide, a work carriage, means for attaching the same to the free end of the first link, and means 55 for adjusting the amount of motion of said carriage.

10. A feed for punch presses and the like, comprising a link one end of which is connected eccentrically to the shaft of the press and free to 55 oscillate about and perpendicular to the axis of that shaft, a guide for the other end of the link attached to the bed of the punch press in a line parallel to the axis of the shaft, the link being slidably mounted on such guide and being free to 60 oscillate in and at right angles to the axis of the guide, a work carriage, means for attaching the work carriage to the sliding end of the first link, and means for varying the timing of 65 the feed with reference to the stroke.

11. A feed for punch presses and the like, comprising a link, one end of which is connected eccentrically to the shaft of the press and free to oscillate about and perpendicular to the axis of 70 that shaft, and a second link one end of which is pivoted to the first link, the other end being attached to the bed of the press and free to oscillate about an axis parallel to the axis of the 75 shaft, a carriage for the work, means to connect the carriage to the free end of the first link, and 80

means for varying the timing of the feed with reference to the stroke.

12. A feed for punch presses and the like, comprising a link, one end of which is connected eccentrically to the shaft of the press, and free to oscillate about and perpendicular to the axis of that shaft, the other end of the link being slidably mounted on a guide causing it to move in a line parallel to the axis of the shaft and being free to oscillate in and at right angles to the axis of the guide, a second link, one end of which is pivoted to the first link between the ends thereof, the other end of which is fixed to the bed and free to oscillate about the axis of the guide, a work carriage, means for attaching the same to the free end of the first link, and means for varying the timing of the feed with reference to the stroke.

13. A feed for punch presses and the like, comprising a link one end of which is connected eccentrically to the shaft of the press and free to oscillate about and perpendicular to the axis of that shaft, a guide for the other end of the link attached to the bed of the punch press in a line parallel to the axis of the shaft, the link being slidably mounted on such guide and being free to oscillate in and at right angles to the axis of the guide, a work carriage, and flexible means of attaching the work carriage to the sliding end 30 of the first link.

14. A feed for punch presses and the like, comprising a link, one end of which is connected eccentrically to the shaft of the press and free to oscillate about and perpendicular to the axis of that shaft, and a second link one end of which is pivoted to the first link, the other end being attached to the bed of the press and free to oscillate about an axis parallel to the axis of the shaft, a carriage for the work, and flexible means 40 to connect the carriage to the free end of the first link.

15. A feed for punch presses and the like, comprising a link, one end of which is connected eccentrically to the shaft of the press, and free to oscillate about and perpendicular to the axis of that shaft, the other end of the link being slidably mounted on a guide causing it to move in a line parallel to the axis of the shaft, and being free to oscillate in and at right angles to the axis of the guide, a second link one end of which is pivoted to the first link between the ends thereof, the other end of which is fixed to the bed and free to oscillate about the axis of the guide, a work carriage and flexible means for attaching 50 the same to the free end of the first link.

16. A feed for punch presses and the like, comprising a link, one end of which is connected eccentrically to the shaft of the press and free to oscillate about and perpendicular to the axis of that shaft, a guide for the other end of the link attached to the bed of the punch press in a line parallel to the axis of the shaft, the link being slidably mounted on such guide and being free to oscillate in and at right angles to the axis of the guide, a work carriage, means for attaching the work carriage to the sliding end of the first link, means for varying the timing of the feed with reference to the stroke, and means for adjusting the amount of motion of said carriage.

17. A feed for punch presses and the like, comprising a link, one end of which is connected eccentrically to the shaft of the press and free to oscillate about and perpendicular to the axis of that shaft, and a second link one end of which is pivoted to the first link, the other end being

attached to the bed of the press and free to oscillate about an axis parallel to the axis of the shaft, a carriage for the work, means to connect the carriage to the free end of the first link, means for varying the timing of the feed with reference to the stroke, and means for adjusting the amount of motion of said carriage.

18. A feed for punch presses and the like, comprising a link, one end of which is connected eccentrically to the shaft of the press, and free to oscillate about and perpendicular to the axis of that shaft, the other end of the link being slidably mounted on a guide causing it to move in a line parallel to the axis of the shaft, and being free to oscillate in and at right angles to the axis of the guide, a second link, one end of which is pivoted to the first link between the ends thereof, the other end of which is fixed to the bed and free to oscillate about the axis of the guide, a work carriage, means for attaching the same to the free 20 end of the first link, means for varying the timing of the feed with reference to the stroke, and means for adjusting the amount of motion of said carriage.

19. A feed for punch presses and the like, comprising a link, one end of which is connected eccentrically to the shaft of the press and free to oscillate about and perpendicular to the axis of that shaft, a guide for the other end of the link attached to the bed of the punch press in a line parallel to the axis of the shaft, the link being slidably mounted on such guide and being free to oscillate in and at right angles to the axis of the guide, a work carriage, means for attaching the work carriage to the sliding end of the first 30 link, means for varying the timing of the feed with reference to the stroke, and means for adjusting the amount of motion of the work carriage.

20. A feed for punch presses and the like, comprising a link, one end of which is connected eccentrically to the shaft of the press and free to oscillate about and perpendicular to the axis of that shaft, and a second link one end of which is pivoted to the first link, the other end being attached to the bed of the press and free to oscillate 40 about an axis parallel to the axis of the shaft, a carriage for the work, means to connect the carriage to the free end of the first link, means for varying the timing of the feed with reference to the stroke, and means for adjusting the amount of motion of the work carriage.

21. A feed for punch presses and the like, comprising a link, one end of which is connected eccentrically to the shaft of the press, and free to oscillate about and perpendicular to the axis of that shaft, the other end of the link being slidably mounted on a guide causing it to move in a line parallel to the axis of the shaft and being free to oscillate in and at right angles to the axis of the guide, a second link, one end of which is pivoted to the first link between the ends thereof, the other end of which is fixed to the bed and free to oscillate about the axis of the guide, a work carriage, means for attaching the same to the free end of the first link, means for varying the timing of the feed with reference to the stroke, and means for adjusting the amount of motion of the work carriage.

22. A feeding device for an intermittently operating machine having a drive shaft, comprising a link, means for connecting one end of the link to the shaft of the machine to cause said end to oscillate in a plane normal to the shaft, a guide for the other end of the link attached to the machine in a line parallel to the axis of the shaft, the 70 75

link being slidingly mounted in the guide, a reciprocatory work carriage, means for attaching the work carriage to the sliding end of the link, means for varying the timing of the feed with reference to the stroke, and means for adjusting the stroke of the work carriage.

23. A feeding device for an intermittently operating machine having a rotary drive shaft comprising a link, means for driving one end of the link from the drive shaft through a to and fro movement, a guide for the other end of the link attached to the machine in a line parallel to the axis of the shaft, said guide causing the end of the link to travel in a path parallel to the axis of the shaft, and an oscillatory support having a to and fro movement for medially supporting said link which actuates said support.

24. A feeding device for an intermittently operating machine having a drive shaft mounted in a frame, said feeding device comprising a link having one end interconnected to the shaft for movement through a circular path, a guide extending parallel to the axis of the shaft for guiding the opposite end of the link, and a second link having one end pivotally mounted upon the frame of the machine, the opposite end of the second link being pivotally attached to a medial portion of the first link cooperating therewith to translate the rotary motion imparted to the one end of the first link into reciprocatory motion at the opposite end thereof.
